UNITED STATES PATENT OFFICE.

EMILY McCOWAN, OF NEW YORK, N. Y.

DESIGN FOR A DOLL.

Application filed December 4, 1922. Serial No. 4,495. Term of patent 7 years.

To all whom it may concern:

Be it known that I, EMILY McCOWAN, a citizen of the United States, and a resident of the city of New York, borough of Manhattan, in the county and State of New York, have invented a new, original, and ornamental Design for Dolls, of which the following is a specification, reference being had to the accompanying drawing, forming part thereof.

The figure is a plan view of a doll, showing my new design.

I claim:

The ornamental design for a doll, as shown.

EMILY McCOWAN.
